UNITED STATES PATENT OFFICE.

GEORGE ARTHUR FRITSCH, OF RENFREW, ONTARIO, CANADA.

SWITCH-ACTUATING MECHANISM.

1,264,382.

Specification of Letters Patent. Patented Apr. 30, 1918.

Application filed August 4, 1917. Serial No. 184,510.

To all whom it may concern:

Be it known that I, GEORGE A. FRITSCH, a subject of the King of Great Britain, and resident of the town of Renfrew, in the Province of Ontario, in the Dominion of Canada, have invented certain new and useful Improvements in Switch-Actuating Mechanism, of which the following is a specification.

This invention relates to improvements in electric switches of the clock operating type, such as described in my United States Patent No. 1207531, and the objects of the invention are to facilitate automatically 10 setting the switch, to simplify the arrangement of the several parts, so that they may be readily open to inspection and repair, and generally to adapt the several parts to better perform the functions required of 20 them.

For having a complete understanding of my invention reference is made to the accompanying drawings in which:

Figure 1 is a fragmentary sectional elevation of the casing showing the location of 25 the switch.

Fig. 2, is a transverse section of the same.

Fig. 3 is a fragmentary front elevation of the casing.

Fig. 4 is a diagrammatic view of the plunger and ratchet key.

Like characters of reference refer to like parts in the several figures.

Referring to the drawings, A represents 35 the improved switch comprising the casing 10 adapted to house the mechanism.

The switch is designed to be actuated by a clock, the shaft 11 of which extends into the casing 10 and is provided with the 40 pinion 12, adapted to mesh with the pinion 13 carried by the spindle 9. This spindle is provided on the outer end with a hand 14, superimposed on a dial 15 which is carried by a sleeve 17 surrounding the spindle 9, 45 and on this sleeve the pinion 13 is mounted. A hand 16 is mounted on the end of the sleeve 17 and is superimposed on the dial 15, which in the embodiment illustrated consists of two concentric circles, on which are 50 engraved the numbers 1-12, the large hand 14 being designed to indicate when the switch is to be closed, while a smaller hand 16 is designed to indicate when the contact is to be broken.

On the spindle 9, a lever 19 is mounted 55 and provided with a spring-controlled pawl

20 adapted to engage with the disk 21, mounted on the pinion 13, while a second lever 22 is mounted on the spindle 9, directly opposite the lever 19, and is also provided with a spring-controlled pawl 23 adapted to engage with the said ratchet disk.

Below the spindle 9 a casing 24 is rotatably mounted on the spindle 25 and in 60 this casing a coil spring 26 is located, having its inner end attached to the spindle, while its outer end is connected to the inner periphery of the casing, and this casing is provided with a peripheral recess 27, adapted to engage with the spring-controlled pawl 28, mounted on the casing 10. The casing 24 is further provided with the lever 29 offset at the upper end as shown at 30 and into this lever a rod 31 extends, and is connected 70 at one end to the arm 32 of the spring-controlled pawl 33 carried by the casing.

That end of the rod 32 projecting through the arm 29 is provided with a pin 34, so that as the arm 29 moves backwardly and forwardly, it will release and reset the pawl 33 in a manner to be made clear hereafter.

Rotatably mounted on the spindle 25 is a 80 casing 35 housing a spiral spring 36, the inner end of which is secured to the said spindle, while the outer end is connected to the inner periphery of the casing, and this casing is provided with an integral arm 37 having a recess 38 in the upper end adapted to co-act with the pawl 33.

This arm is designed to engage with the plunger 39 which operates the key 40, and opens or closes the circuit, in which the switch is installed. The upward movement 90 of the arm 37 of the casing 35 is limited by a pin 41, carried by the casing 24 adjacent to which the casing 35 is mounted.

When this switch is in use, the hand 14 is set at the hour to which the key 40 is to be closed, and the hand 16 is set at the hour 100 at which the circuit is to be broken, and the clock shaft 11 will transmit its motion through the pinion 12, to the pinion 13 causing the lever 19 to engage with the pawl 28 and liberate the same, permitting of the casing 24 being rotated in the clockwise direction, so that the arm 37 engages the plunger 39 co-acting with a key 40.

In this position the rod 31 will rock the 110 pawl 33 and cause it to engage with the recess 38 in the arm 37 in a downward or depressed condition. As the clock spindle

continues in its motion the lever 22 is ultimately brought into contact with the offset end of the arm 29, so rotating the casing 24, in a counterclockwise direction, and when 5 the lever 29 engages with the pin 34, a rocking motion is transmitted through the arm 32 to the pawl 33, so releasing the arm 37 which will be rotated backwardly under the action of the spring 36, until the said arm 10 engages with the pin 41.

The switch is now reset and the above operation will be repeated automatically every 24 hours. When the casing 24 is rotated in the clockwise direction the pawl 28 reengages the recess 27 holding the casing 24 with the arm 37 in its upward position, 15 until further operation of the switch takes place.

From this description it will be seen that 20 I have invented a switch, which can be advantageously utilized in conjunction with my improved switch shown in United States Patent No. 1,207,531, and in which the switch will be automatically reset at predetermined intervals.

As many changes could be made in the above description and many apparently widely different embodiments of my invention within the scope of the claims constructed without departing from the spirit 30 or scope thereof, it is intended that all mat-

ter contained in the accompanying specification and drawings shall be interpreted as illustrative and not in a limited sense.

What I claim as my invention is:

1. In a switch of the class described, a pivotally mounted casing, an arm on the casing having an offset end, a second casing pivotally mounted to the first said casing, resilient means controlling the operation of 40 first said casing, an arm on the second casing, a pin limiting the movement of the arm, and clock means designed to control the rotations of the first casing.

2. In a switch of the class described, a pivotally mounted casing, resilient means for rotating the casing, a second casing located adjacent to the first casing, and provided with an integral arm, a pin on the first casing controlling the operations of the 45 arm, an arm on the first casing having an offset end, a pawl engaging with the first arm actuated by the second arm, a pawl controlling the movement of the first casing and clock means for liberating the second 50 pawl.

In witness whereof I have hereunto set my hand in the presence of two witnesses.

GEORGE ARTHUR FRITSCH.
